MATCH DEVICE

William M. Young, Harrisburg, Pa.

Application July 3, 1933, Serial No. 678,953

7 Claims. (Cl. 206—29)

My present invention, in its broad aspect, has to do with improvements in match packets, particularly those known as paper match packets, and is designed to provide a structure wherein the match is ignited when withdrawn from the packet. By the term "packet" I mean any means used to carry a match, such for instance as a cigar band carrying a match, a paper cover for cigarette packages carrying matches, or a series of match units carried in a container strip from which certain units may be torn off or severed. More particularly, it is my purpose to provide means for retaining a match in such a position that the "head" of the match is positively retained out of the way of the substance against which the head must be contacted and scratched in order to be ignited until the match is withdrawn for ignition and use. By this means my device is rendered safe and "fool-proof". Furthermore, my device provides for means for shielding and covering the material against which the match head must be contacted and scratched in order to be ignited to the end that such material will not become damp or wet or otherwise rendered inapt for use.

My invention may be adapted for use in mounting a match or matches on a cigar band; in mounting matches on cigarette packages, or packages for tobacco and the like; for mounting matches in strips or packets, and in various other ways, to the end that when a match is withdrawn from its container or mounting it will be automatically and surely ignited. In addition to these uses, my invention may be used in conjunction with ash trays, wall card matches, humidores, pouches, continuous strips formed in any shape for carrying matches, and for any and all other purposes to which matches or match containers may be put. Furthermore any number of matches may be used with my invention, and it is especially adapted for modification in shape and details of form to particular purposes, all of which would be within the inventive concept herein described.

In addition to the above advantages and purposes others of equal importance will be apparent as the detailed description proceeds, and to that end I desire to emphasize that interpretation of the invention should only be conclusive when made in the light of the appended claims.

In the drawings wherein I have shown several forms of my invention:

Figure 1 is a view showing the manner in which a match is attached to its support or container;

Figure 2 is a view showing the manner of folding the match so that the head is positioned within the container;

Figure 3 is a view showing a match partially withdrawn from its container and in position to contact with the igniting surface within the container so that as the match is withdrawn therefrom it is automatically ignited;

Figure 4 is a view showing a match fully withdrawn and ignited by contact with the igniting surface;

Figure 5 is a fragmentary view showing the match stem protruding from the container or packet so that it may be properly grasped for withdrawal;

Figure 6 is an edge view of a match packet constructed after the dictates of my invention;

Figure 7 is a view of a blank designed to be formed into a cigar band carrying one or more matches;

Figure 8 is a perspective view of a cigar band formed to carry one or more matches of the type embodying my invention;

Figure 9 is a view of a blank used to apply my invention to a packet of cigarettes, in which case sufficient matches are furnished to ignite the several cigarettes in the package;

Figure 10 is a perspective view of a package of cigarettes embodying my invention;

Figure 11 is a view of a blank used to form double-row packets of matches embodying my invention;

Figure 12 is a view of a part of a strip embodying double-row packages of matches, and

Figure 13 is a view of a strip embodying single-row packets of matches constructed in accordance with my invention.

In the drawings wherein like characters of reference are used to designate like or similar parts throughout the several views thereof:

The numeral 1 designates a strip of suitable material, such as cardboard or the like which is folded lengthwise to provide a front 2 and a back 3; the upper edge of the back 3 has upon its inner face suitable material usually designed to ignite the heads of safety matches, and this material is designated 4 and similar material 4a on the lower edge may be provided. One or more (or any number) of matches 5 are attached to the edge of the back 3 by means of web part 6 which is integral with the material of the strip 1 and with the lateral extension 7 on the match stem 8. On the outer end of the match stem 8 is the head 9, and since the extension 7 is spaced from the lower end of the stem of the match a part 10 remains which provides a projecting finger grip to remove the match from the packet in the manner which will be hereinafter described.

5 10 15 20 25 30 35 40 45 50 55

In practice the strip with all its matches is struck from a single blank of material in one operation of a suitable machine; the match part being integrally connected to the material of the strip by the extension 7 and web part 6. The matches are then folded in to lie against the inner face of the back 3 below the igniting material 4; that is with the heads 9 of the matches below the igniting material 4; the line of fold is between the extensions 7 and the ends of the webs 6, as shown at 11 in Figure 2. This manner of folding the matches in leaves the end 10 of the match stem protruding so that it may be grasped to withdraw the match as shown in Figure 3, rupturing the connection between extension 7 and web 6 so that the head 9 of the match is drawn across the igniting material 4 to automatically ignite the match as it is withdrawn as shown in Figure 4. The front 2 and back 3 may be connected together by stitching 12 as shown in Figure 5, or by gluing the same; stapling, or in any other suitable manner.

In Figure 7, I have shown a blank designed to form a cigar band embodying my invention, in which case the body 13 forms the band encircling the cigar, same being beat to form a band as shown in Figure 8, while the extension 14 is folded over against the body 13 to form a container for the match on the dotted line 15; the match in turn is folded down upon the container after the manner already described in conjunction with Figures 1 to 4 inclusive whereby when a match is withdrawn the head thereof is engaged with the friction material and ignited, and while I have shown one match for each cigar band, any suitable number may be provided.

In Figures 9 and 10, I have shown a series of matches embodying my invention and designed for use with a package of cigarettes. In this case the blank 16 is struck to form a container for all of the matches, and shaped to go about a package of cigarettes. The matches are folded down on the back part of the strip so that the heads are below the igniting material 4 after the manner described in conjunction with Figures 1 to 4 inclusive, in which case the portions 10 protrude to be grasped by the fingers as the matches are used to withdraw the matches and automatically ignite them as withdrawn. The slits 17 facilitate bending the packet. The usual internal revenue stamp is designated 10a.

In Figures 11 and 12, I have shown a packet or packets containing double-rows of matches embodying my invention in which case the blank 18 is folded up on the dotted line 19 after the matches have been folded down after the manner shown in Figures 1 and 2; the two rows are thus separated from each other when folded together to form double rows as shown in Figure 12. The packets may be formed in strips as shown. In Figure 13 a strip embodying single rows of matches is shown, and the strip is formed with tear lines 20 so that units of several matches may be detached and distributed as desired. In each case the inventive concept is that of so folding the matches into the container part that the head is below the igniting material 4 thereby providing a safe device of general utility, and one which is adaptable for use in any way in which matches are generally used.

While in the foregoing I have described my invention as applied to match packets, cigar bands, cigarette packages and the like, it is to be understood that this does not limit the number of uses to which my invention may be put; for in-

stance, my invention may be applied to humidors, ash trays, and all kinds of smokers' utensils, also to wall matches, in automobiles (as an accessory on the instrument board) and the like. Neither am I to be limited to the materials used, nor the number of matches contained in any particular article, nor the form of such article. That being the case, it is again emphasized that interpretation of my invention should only be conclusive when made in the light of the subjoined claims. 10

I claim:

1. A match device comprising a blank cut to form a plurality of matches and a body portion, the body portion bent to form a container and having igniting material on one of the inner walls thereof, and the matches having integral, lateral extensions located intermediate their ends, webs integrally connecting the extensions with the body portion, said webs lying substantially parallel with the match stems, and said matches folded over at the points where the extensions join the webs to dispose the heads of the matches adjacent the igniting material and the free ends of the stems outside the container to form finger grips to withdraw the matches from the container. 25

2. A match device comprising a body portion, a plurality of matches, each match having a lateral extension, and the body portion having upstanding webs integrally connected with each extension, the extensions on the matches being intermediate the ends of the stems thereof, and said matches folded over at the point of connection of the extensions with the webs to dispose their heads against the surface of the body portion and the ends of the stems projecting therefrom, and igniting material on the surface of the body portion disposed out of contact with the heads of the matches but in line with the path of withdrawal of the matches when grasped by the projecting parts and drawn out to sever the extensions from the webs thereby to ignite the matches simultaneously with detachment of the matches from the body portion. 40

3. A match device comprising a body portion 45 for attachment to a cigar, a package of cigarettes, or tobacco or the like, a plurality of matches each having a lateral integral extension thereon intermediate its ends, a plurality of webs integral with the body portion and each integrally connected to an extension on a match, said webs disposed between the matches when the matches are bent over at the points where the extensions join the webs, the body portion having igniting material on an inner surface, and the matches 55 when bent in to have their heads concealed within the body portion being disposed with their heads adjacent the igniting material with the free lower ends of the match stems protruding from the body portion to provide finger grips for 60 withdrawing the matches.

4. A match device comprising a foldable body portion having igniting material thereon, a plurality of matches, each match having a lateral extension intermediate its ends, a web connecting each extension with the body portion, and said matches adapted to be folded over at the point of connection of the extensions with the webs to dispose the heads of the matches within the body adjacent the igniting material when 70 folded with the ends of the stems projecting therefrom.

5. A match device comprising a body portion having igniting material thereon and adapted to be folded over upon itself to form a cover, a plu- 75

rality of spaced apart matches on the body, each match having a lateral extension intermediate its ends, webs in the spaces between the matches, each web connecting an extension with the body portion, and said matches adapted to be folded over at the point of connection of the extensions with the webs to dispose the heads of the matches within the folded body adjacent the igniting material with the ends of the stems projecting therefrom.

6. A match device comprising a body formed to provide a cover and having igniting material in conjunction therewith, a plurality of matches, each match having an integral lateral extension, a web integrally connecting such extension with the body portion, and said matches adapted to be folded over to be received in the body with

their heads adjacent the igniting material and with their ends extending out therefrom.

7. A match device comprising a blank cut to form a body and having igniting material in conjunction therewith and a plurality of match stems connected with the body by integral webs, each connected with an integral, lateral extension on the match stem and intermediate the ends thereof so that when the match stem is folded over against the body at the point of connection between the web and extension a part of the match will lie within the body when folded with the head of the match adjacent the igniting material and end thereof will project out from the body.
